UNITED STATES PATENT OFFICE.

PHILIP DWYER AND JACOB OTTMANN, OF NEW YORK, N. Y.

NON-REFILLABLE BOTTLE.

No. 872,913.

Specification of Letters Patent.

Patented Dec. 3, 1907.

Application filed April 4, 1907. Serial No. 366,295.

To all whom it may concern:

Be it known that we, PHILIP DWYER and JACOB OTTMANN, both citizens of the United States, and residents of the city of New York, borough of Manhattan, in the county and State of New York, have invented a new and Improved Non-Refillable Bottle, of which the following is a full, clear, and exact description.

10 This invention has for its object to provide means adapted to prevent a bottle from being re-filled, and consists of the device hereinafter described and illustrated in the accompanying drawings, in which drawings

15 Figure 1 is a vertical section on the line 1—1 of Fig. 3, of a device embodying our invention applied to the neck of a bottle; Fig. 2 is a vertical section partly in side elevation, of a tube embodying our invention; Fig. 3 is a horizontal section, taken on the line 3—3 of Fig. 1; and Fig. 4 is a horizontal section, taken on the line 4—4 of Fig. 2.

Similar characters of reference indicate corresponding parts in all the views.

25 As illustrated in the drawings, 1 represents the neck of a bottle, which may be of ordinary construction, within which is arranged a tube bent to form a loop, consisting of legs

3 and 4 and an intermediate section 5 joined 30 to said legs by means of bends 6 and 7. The leg 3 and intermediate section 5 are each provided with valve seats 8 and 9 respectively, off-set from the inner wall of the tube and adapted to receive conical valves 10 and 11

35 constructed with converging side walls so as to make the valves self-centering in their respective seats. The valves 10 and 11 have a limited free movement in the tube, which movement is controlled by means of stops 12 and 13 formed by compressing inward the side walls of the tube. The ends of the legs 3 and 4 are preferably provided with flaring

40 mouths 14 and 15 respectively, having connected therewith a vent tube 19 provided 45 with a valve 20 arranged with its pointed end facing the mouth 14 of the main tube. When in use the flaring mouth 14 of the leg 3 is arranged inner-most in the neck and the end 15 outermost. The valve seats 8 and 9, and the

50 valves 10 and 11 are so constructed and arranged that the pointed end of the valve 10 faces in the direction of the flaring mouth 14 of the tube, while the reduced end of the valve 11 extends in the direction of the outer end 15 of the tube. The tube is arranged within the neck of the bottle and secured

therein by means of a body of cement or other material 16, the upper end 17 of which is preferably stopped short of the outer end of the neck so as to permit a cork 18 to be inserted in the head of the neck, as in bottles of ordinary construction. The means whereby the tube is secured within the neck of the bottle is not material to our invention, however and any other means having similar capabilities may, therefore, be employed if desired.

When the device is in use the bottle is first filled and the tube with its binding is inserted in the neck of the bottle and sealed therein. When the bottle is inverted the liquid therein passes through the flaring mouth 14 of the tube and past the valve 10 and into the central section 5 of the tube, thereby lifting the valve 11 from its seat and permitting the liquid to pass around the bend 7 and through 70 the outer section or leg 4 of the tube. If the bottle is arranged in an upright position, however, the liquid cannot be passed into the bottle through the end 15 of the tube for the reason that the valve 10 is then closed on its 80 seat.

Having thus described our invention, what we claim as new and desire to secure by Letters Patent is:

1. A bottle having its neck provided with 85 a discharge tube having a central loop and end sections, and provided with oppositely disposed valve seats formed in the central and inner end section, and self centering valves adapted to bear on said seats and extending in opposite directions.

2. A bottle having a neck provided with a tube bent to form a loop, comprising a central and end sections, the central and one of the end sections being provided with oppositely disposed valve seats, and stops spaced from said seats, and self centering valves facing in opposite directions adapted to bear on said seats.

3. A bottle having its neck provided with 100 a tube bent to form a loop, comprising a central and end sections, the central and the inner end section being provided with valve seats facing in opposite directions and provided with stops spaced from said valve seats, the inner end section being provided with a flaring mouth, and self-centering valves facing in opposite directions adapted to bear against said seats.

4. A bottle having its neck provided with 110 a tube arranged therein terminating at its outer end short of the extremity of said

neck, and comprising a loop forming a central and end portions, the central and inner end portion being provided with oppositely disposed valve seats and stops spaced from 5 said seats, and self centering valves facing in opposite directions and adapted to bear on said seats.

In testimony whereof we have signed our

names to this specification in the presence of two subscribing witnesses.

PHILIP DWYER.
JACOB OTTMANN.
